ATTORNEY

UNITED STATES PATENT OFFICE.

WALTER MAJESKI, OF NEW YORK, N. Y.

ADJUSTABLE REED IN WIND INSTRUMENTS.

Application filed March 11, 1924. Serial No. 698,354.

To all whom it may concern:

Be it known that I, WALTER MAJESKI, a citizen of Poland, and resident of New York, in the county of New York and State 5 of New York, have invented certain new and useful Improvements in Adjustable Reeds in Wind Instruments, of which the following is a specification.

The invention relates to an improved form 10 of reed for saxophone or similar musical instrument.

The primary object of the invention is to provide a form of reed which can be readily adjusted to vary the clearance of the reed 15 with respect to the mouthpiece of the instrument.

The mouthpiece of such instruments are usually formed of hard rubber or other composition which is difficult to cut away after 20 the mouthpiece is formed, and are provided on the top side with a flat face. A reed usually formed of a thin plate of spruce, cane, or other vibratory wood is fitted to seat on this flat face and is demountably 25 secured in place by means of a suitable encircling clamp.

Numerous means have been suggested to 30 adjust the reed to vary the interval between the vibratory end of the reed and the inlet opening formed in the flat surface of the mouthpiece; the usual practice being to cut away the mouthpiece to form a depression therein so that by varying the tension on the 35 encircling clamp the vibratory end of the reed may be sprung into any desired adjustment relative to the mouthpiece.

Any mutilation of the mouthpiece is 40 objectionable, among other reasons, due to the fact that this practice is apt to create uncontrollable air leakages past the reed and, further, some players do not desire this adjustable feature and if so, only to a limited extent, which necessitates different forms of recesses formed in the mouthpieces when 45 marketed to meet the demands of different players.

Accordingly, another object of the invention is to provide a cheap, inexpensive means 50 for obtaining any desired adjustment which can be applied to and used with, any of the conventional forms of mouthpieces now in general use without necessity of mutilating the mouthpiece.

I attain this object of the invention broad- 55 ly by marketing a new form of reed so that with a standard form of mouthpiece dif-

ferent players can select that particular form of reed which best suits his requirements. In the form herein selected for discussion the reed resembles conventional forms as far 60 as possible and differs simply in that the body portion is formed into a springy bridge designed to fit on the flat face of the mouthpiece and designed to be engaged by the conventional clamp to provide a minute ad- 65 justment of the vibratory tongue or end which overlaps the inlet opening in the mouthpiece.

Various other objects and advantages of the invention will be in part obvious from 70 an inspection of the accompanying drawings and in part will be more fully set forth in the following particular description of one form of mechanism embodying 75 my invention, and the invention also consists in certain new and novel features of construction and combination of parts hereinafter set forth and claimed.

In the accompanying drawings:—

Figure 1 is a perspective view of a conventional form of mouthpiece equipped with 80 a preferred embodiment of the invention; and

Figure 2 is a vertical sectional view taken axially through the mouthpiece shown in 85 Figure 1.

In the following description and in the claims, parts will be identified by specific names for convenience of expression but they are intended to be as generic in their 90 application to similar parts as the art will permit.

In the drawings there is shown a musical instrument indicated symbolically by the tube 10 into which is fitted a mouthpiece 11. 95 The mouthpiece is provided on its upper side with a flat face 12 through which extends the intake opening 12 all as is well known in devices of this character.

Positioned on the flat face 12 is a single 100 length reed 13 of vibratory material in general resembling the similar forms of reeds which are now sold as replacement parts of these instruments. The reed 13 comprises a relatively thick body portion 14 reducing 105 in thickness to a vibratory tongue end 15. The body portion 14 is provided on the side facing the face 12 with a transversely extending groove or recess 16 which thus acts to form the body portion as a bridge por- 110 tion. Encircling the bridge portion in a clamping ring 17 carrying on its upper side

- a clamping screw 18 which is designed to react through a washer 19 and bear on the bridge portion. The pressure of the screw causes the arching bridge to become depressed and in this way cause the unclamped portion of the reed to swing about the fulcrum 19 and thus adjust the vibratory tongue 15 to vary the clearance 20 between the tongue and the adjacent edge of the mouthpiece. By a careful manipulation of the screw any desired adjustment within the range of movement of the vibratory end may be attained and thus the clearance can be adjusted from time to time by the player.
- 15 When the reed is damaged or worn screw 18 is loosened, the old reed slipped out from the clamp and a new reed inserted in place.
- The reeds are made up in sets having different vibratory characteristics and with some of the bridge sections stiffer than others to meet demands for varying degrees of rigidity and elasticity. These reeds are usually sold in packages of about one-half dozen to each package and the purchaser selects that type of reed which best suits his particular requirements.
- 20 Having thus described my invention, I claim:
- 25 1. In a reed musical instrument, the combination of a mouth-piece provided with a
- flat face, a reed formed of one-piece of resilient material and including a relatively thick body portion reducing in thickness towards one end to form a vibratory tongue, the body portion having its underside engaging the flat face of the mouth-piece, said underside provided with a recess extending transversely entirely across the same thereby to cause the body portion to bridge across the flat face, a clamp encircling the reed and mouth-piece and extending across the top of the bridging portion of the reed and means for adjusting the bearing engagement of the clamp on the reed thereby to vary the position of its vibratory tongue relative to the flat face of the mouth-piece.
- 30 2. As an article of manufacture, a reed for the mouth-piece of musical instruments comprising a single length of vibratory material being relative thick at one portion and diminishing in thickness therefrom towards one end to form a vibratory tongue, the thick portion provided on the face adapted to engage the mouth-piece with a recess extending transversely and entirely across said face.

Signed at New York in the county of New York and State of New York this 3rd day of March A. D. 1924.

WALTER MAJESKI.
